UNITED STATES PATENT OFFICE.

EDMUND JACH, OF MILWAUKEE, WISCONSIN.

LOCKING DEVICE FOR THE GAS COCKS OF STOVES, RANGES, AND HEATERS.

Application filed April 30, 1926. Serial No. 105,758.

The present invention relates to an improved device for locking the gas cocks of, for instance, a kitchen range, so that the cocks may not be opened to permit the flow 5 of gas until after the locking device has been moved to unlocking position. In modern kitchen gas ranges the usual pilot light located at some distance from the gas cocks, requires one hand of a person in its operation to shoot the jet of flame over to the desired burner, while the gas cock requires the other hand of a person in its operation to open the flow of gas.

The gas cocks of kitchen ranges, stoves 15 and heaters are sources of constant danger to life and property by reason of being accidentally operated so as to open the flow of gas, and also for the reason that children of immature years are prone to turn them on 20 without a realization of the disastrous results that may follow their thoughtless acts.

Safety devices for gas cocks have been patented heretofore, but none of these are adapted for use in the now popular form 25 of kitchen ranges which are provided with pilot lights, requiring one hand of the person for operation. My invention is embodied in a construction of gas cocks provided with a locking device, in which the locking device may be moved into unlocking position, and the gas cock turned by one hand, leaving the other hand free to operate the pilot light.

The invention resides in certain details of 35 construction which will be more fully described in this specification, and the novelty thereof will be pointed out in the appended claims.

In the accompanying drawing:

Figure 1 is a view in elevation of my improved device, looking toward the gas range of which it is a part, and showing in phantom how the same is operated by one hand of a person.

Fig. 2 is a vertical sectional view in the central plane of Fig. 1, showing details of construction, with certain elements in full lines.

Fig. 3 is a horizontal section on the irregular line 3-3, Fig. 2.

In the drawing, the barrel 10 of the gas cock is formed as a casting having a hollow extension 11 at the right thereof and a lug 12 at the front thereof, formed integrally therewith. Fitted into the barrel is the usual valve 13, provided with a pass 14, which

may be aligned with the source of supply 15 and the burner connection 16, by rotating the valve 13 90° through operation of the valve handle 17.

The hollow extension 11 receives a locking pin 18, actuated by a spring 19 confined by a cap 20 threaded on the outer end of the extension 11. The valve 13 is provided with a shallow bore 21 which is entered by the 60 inner end of the locking pin 18 when the parts are in the positions shown, and the arrangement shown and described will prevent rotation of the valve 13 until after the end of the spring pressed locking pin 18 65 has been withdrawn from its engagement with the bore 21. Upon withdrawal of the spring pressed locking pin 18, the valve may be partially rotated to permit the flow of gas, such rotation being limited by the 70 pin 22 set in the valve, as is usual in devices of this class.

To permit the use of a device for the present purpose in modern gas ranges provided with pilot lights, the operation of the 80 locking device so as to unlock the valve must be so arranged that such unlocking operation and the partial rotation of the valve to open the same, can be effected by one hand. To enable this to be brought about, 85 I connect to the projecting rear end of the spring pressed pin 18, a push bar 23 extending parallel with the hollow extension 11 and guided in a perforation in the lug 12 on the barrel 10, the free end of the said 90 push bar being extended to a point within easy reach of the thumb of the hand which is used to turn the valve. The manner of operation is indicated in Fig. 1, by the phantom view thereon. As a convenient means 95 of effecting connection between the spring pressed pin 18 and the push bar 23, I place upon the reduced extended end of the said pin a washer 24, passing the perforated bent end of the push bar 23 over the end of the pin, and securing the same in position by means of a nut 25 threaded onto the outer 100 end of the pin 18.

Having thus described my invention, what I claim and desire to secure by Letters Patent of the United States, is:

1. A safety cock for gas stoves, etc., comprising a barrel and a tubular extension therefrom, a valve arranged for partial rotation in the barrel to control the flow of gas, 110 a spring-pressed pin arranged in the tubular extension and engaging a bore in the

valve, such pin acting to prevent rotation of the valve, and a push bar connected at one end to the projecting end of the said pin and serving to withdraw the engaging end 5 thereof from the bore in the valve, and operated by the thumb to permit the valve to be turned.

2. A safety cock for gas stoves, etc., comprising a barrel and a tubular extension 10 therefrom, a valve arranged for partial rotation in the barrel to control the flow of gas, a pin arranged in the tubular extension, a spring confined in said tubular extension by a cap thereon for actuating the

said pin, the valve being provided with a bore engaged by the pin to prevent rotation of the valve, and a push bar connected at one end to the projecting end of the said pin and serving to withdraw the engaging end thereof from the bore in the valve, the said 20 push bar being operated by thumb pressure to permit the valve to be turned by the fingers of the same hand.

In testimony whereof, I have signed my name at Milwaukee, this 17th day of April, 25 1926.

EDMUND JACH.
